UNITED STATES PATENT OFFICE

ELEANOR J. KASTNER, OF GLEN RIDGE, NEW JERSEY, ASSIGNOR TO L. E. WATERMAN COMPANY, OF NEW YORK, N. Y., A CORPORATION OF NEW YORK

DESIGN FOR A RECEPTACLE FOR DESK SETS

Application filed November 8, 1930. Serial No. 37,586. Term of patent 14 years.

To all whom it may concern:

Be it known that I, ELEANOR J. KASTNER, a citizen of the United States, residing at Glen Ridge, in the county of Essex and State of New Jersey, have invented a new, original, and ornamental Design for Receptacle for Desk Sets, of which the following is a specification, reference being had to the accompanying drawing, forming a part thereof.

The figure is a perspective view of the receptacle showing my new design.

I claim:

The ornamental design for a receptacle for desk sets substantially as shown.
